David H. Gilbert of Dorchester, Massachusetts
Sellers' Patent

The substance of record in these letters Patent and making part of the same, consisting of a description in the words of the said David H. Gilbert himself of his improvement in the mode of driving water-wheels by water and in the structures for that purpose.

To all to whom these presents shall come, David H. Gilbert of Dorchester in the County of Norfolk and Commonwealth of Massachusetts, will aight cordially Greeting. Be it Known that of the said Gilbert have invented and constructed and applied to water a new and useful improvement in the mode of driving Water-wheels by water and in the structures for that purpose. Which invention and improvement I describe as follow: That is to say, further to the understanding thereof, as far as the drawings annexed, which is to be taken and construed as a part of this specification.

Figure number one in the said drawing is intended to represent the water-wheel and its axle within it and parts of the frame of the flume connected with it. A. A. A. designates the part of the figure intended to represent the water-wheel which revolves around the axle upon a vertical axis, which passes ap through the centre of the axle. a. a. a. &c. designate the parts intended to represent the back of the water-wheel, and designates the vertical axis before mentioned which turns and is guided by K. turns on a bearing in the way, K. being part of the frame of the flume. B. B. B. B. designates the parts of the figure intended to represent the parts of the frame of the flume which is connected with the axle. C. designates that part of the frame which is above the water-wheel, which turns around with it.

Figure number two in the said drawing is intended to represent a horizontal section of the water-wheel & of the axle within it and around which it revolves and a vertical shaft passing up through the centre of the said axle at c. A. A. A. in this figure designate that part of it intended to represent the back of the water-wheel which is also represented with its arms in figure number one in the said drawing. These arms designated by f. f. f. in said figure

conditions are in the lower part and on the only arms of the wheel. The upper arm of the wheel is not shown in the figure, and numbered two, in order that the brackets may be attached which are between the upper and lower arm fixed in position on the wheel. These brackets are in the form of a case, as represented in the figure, and will have a back from 12 to 18 inches high, altho they may be made in the form of an elbow, or in another different shape to answer the purpose. In this case, the wheel of ten feet in diameter, these brackets may be about one inch high up to, but they may be further or nearer from 12 to each other, or receding or approaching according to the size of the wheel, and the quantity of water to be let upon it.

These brackets are designated by and 4C, in the back figure numbered two. L. b. b. b. designates the front of the back figure numbered two, and is to be placed to the back of the back cistern in which the water-wheel is set. The sides of the cistern are so constructed that parts of them from A to M, before each other, do not have apertures and the form of a case from the middle of the cistern out to the outside of the cistern at M, this which is further gates C, C, C, C, are open the water, so the cistern may rise and strike upon P, into the brackets of the wheel. These apertures are to be made larger at the mouth inside of the cistern when the gates are there at the outside at M, when the water issues upon the brackets of the wheel, and should gradually decrease in size from A to M, as represented in the figure numbered two. They may be larger or smaller according to the size of the wheel and the power required. For a wheel ten feet in diameter with brackets fifteen inches in length and one makes upon the brackets may be about eight inches wide at the mouth, down the sides of the cistern, and about four inches, or less at the mouth, in outside of the cistern. But these apertures may be larger or smaller according to the size of the wheel, the quantity of water to be let upon it and the power required.

The sides of the case are made to lay over each other, and they may be made 14 by 10, or much or about ten foot, so as to make the length of these apertures about ten feet, but they may be much longer or shorter at discretion. For a wheel of this diameter, about ten feet, there may be from four to six apertures, but the number may be made of 6, according to the size of the wheel, the quantity

the water wheel, and the pressure equal. The jaws of each of the above gates, with the wheel, fifteen inches apart, so that the buckets may be about fifteen inches long, and on the back the spaces, varying, be about fifteen inches high, at the head height, on the top of the buckets of the wheel 5555, during the time of the water. These gates must correspond in number with the apertures of the buckets, to complete and alter the pressure and speed of the wheel, proportionately to time, but otherwise these gates may be dispensed with, and a main gate to the flame connected with the cistern will answer very well. The use of the water-tube the apertures is intended to be represented by the arrows in figure 149. The top of the cistern should be about six inches above the outer rim of the water-wheel, so that the water may be about six inches above the top of the water-wheel, the water-wheel being mounted on the water-wheel, and the sides of the cistern shall be so adapted to each other that the wheel may revolve around the cistern as easily and closely to it as it can conveniently be made to do without friction. D. designates the bottom of the cistern, forming a hole containing the water to be let out, thus the apertures upon the back of the water-wheel. The cistern is fastened to the water-wheel, so as to be removed in case of the quantity in the cistern is to be increased, as is directed in the figure in the second volume of the journal of the Franklin Institution at page eighty seven. Another use of this cistern is, given in figure numbered five in said drawing. The rim which crosses over the top of the said aperture A is to form a sort of curved tube from the gates at the inner mouth, d. to the outer mouth, n. is seen in the figure - being denoted by C.C.C.C. The gates are represented as before by C.C.C.C. The rim of the gates by 5555, by the turning of which the gates are to be opened or shut, or partly opened or shut at pleasure. These gates however may be made to open by lifting, or represent the outer mouth of the apertures. The flame is immediately above the cistern, and is adapted to it, so as to fit to it, water light, in order to prevent the escape of water.

The flame must be large enough to keep up the head of water required to act upon the wheel. For a wheel of the above dimensions, a flame about twelve feet wide and about fifteen feet in length will answer the purpose.

The buckets of the wheel should be of metal, as well as the arms, and shaft, and the whole wheel and cistern may also be of metal, as the wood will an-

150.

has the purpose, the use of the wharf and of carrying the same structure & part of the fleet away to port, so as to be ready to be placed again in full quantity and kind of force. It will be situated in the manner above described and constructed and be associated with the station constructed as above described, and known by name to be the "Landing Stage" or "Cape Henlopen Landing Stage" and will be described in copy. It will be equipped entirely with a promontory of water, and will open to the effect when the tide is out, the water remaining in the Harbor in back water, and regardless of the tide, and is more free from obstruction by frost or ice than any other wharf.

That I claim as my invention and improvement in the construction and use of such wharf as above described and such wharf within these claims, the wharf and station, and the wharf and station with each other for the purpose of laying such wharf by water to carry mills or machinery of any kind down by water.

In testimony of what the above is a true specification of my invention and improvement, I do here make and sign this 25th day of December in the year of our Lord eighteen hundred and thirty three.
